(No Model.)

V. A. THOMAS.
DETACHABLE STEP FOR POLES.

No. 459,844.

Patented Sept. 22, 1891.

UNITED STATES PATENT OFFICE.

VAN A. THOMAS, OF PROVIDENCE, RHODE ISLAND, ASSIGNOR OF ONE-HALF
TO ANDREW D. ROSS, OF SAME PLACE.

DETACHABLE STEP FOR POLES.

SPECIFICATION forming part of Letters Patent No. 459,844; dated September 22, 1891.

Application filed December 27, 1890. Serial No. 375,982. (No model.)

To all whom it may concern:

Be it known that I, VAN A. THOMAS, a citizen of the United States, residing at Providence, in the county of Providence and State of Rhode Island, have invented certain new and useful Improvements in Detachable Steps for Poles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In ascending and descending poles used for supporting conducting-wires, cables, &c., employed for electric lighting, telephonic, or telegraphic purposes it has been usual heretofore for the lamp-trimmers, linemen, and others who in the execution of their duties are required to mount the poles to carry about with them a short ladder to enable them to reach the lowest one of a series of conveniently-arranged permanent short steps secured to opposite sides of the pole. Such fixed steps extend, say, from the top of the pole downwardly to within about six feet from the ground, the latter part of the pole being unprovided with steps or other means to facilitate its ascent. The omission of steps from this portion is done to prevent unauthorized persons from mounting the pole. An objection to poles thus unprovided with steps on its lower portion is that it compels the linemen, &c., to carry with them a short ladder by which to mount and reach the first step. Obviously the ladder not only increases the linemen's burden, but it is very inconvenient to carry it through crowded streets.

The object I have in view is to provide poles of the class before referred to with improved means by which they may be readily ascended by the linemen and at the same time dispensing with the use of portable ladders.

To this end my invention consists of a double recessed or socketed plate arranged to be permanently secured to the pole and a step having the top and bottom portions of an end thereof arranged to interlock with the recessed plate.

In the accompanying sheet of drawings,

Figure 1 is a side elevation of a pole embodying my improvement. Fig. 2 is a side view, enlarged, of my invention. Fig. 3 is a plan view. Fig. 4 is a side view in partial section showing the device as in use. Fig. 5 is a front view of the base or plate, which in use is permanently secured to the pole. Fig. 6 is an end view of the removable step or bracket; and Fig. 7 is a side elevation, the plate being in section, showing the manner of inserting and removing the step.

A more detailed description of my invention, including the manner of its operation, is as follows:

A, again referring to the drawings, indicates the device as a whole, the same consisting of the socketed base or plate portion *b*, adapted to be permanently fixed to the pole, and the removable bracket or step proper *a*. The parts may be made of brass or other suitable metal, although I prefer to make them of brass, especially when they are to be used often, as on electric-light poles.

The plate *b* is provided in front with upper and lower projections *b'* *b''*, which form the respective sockets *b³* *b⁴*. The upper or inverted socket *b³* is closed at the top, thereby preventing dirt, &c., for collecting therein. This socket is somewhat wider than the bottom one, which latter is open at top and bottom. The back side of the socket *b³* is concave, as clearly shown in Figs. 4 and 7. The plate itself is provided with holes adapted to receive screws to secure it to the side of the pole. (See Fig. 4.)

The step portion *a* is provided with an end or head arranged to enter the two sockets of the plate *b*. The upper part of the said head extends above and at right angles to the main or horizontal portion of the step, its face being convex, so as to more freely enter and bear against the back of the socket *b³*. The opposite or bottom end of the head is reduced laterally to form a tenon *a²*, adapted to easily enter the lower socket *b⁴*, the sides of the head contiguous to the tenon when in use resting firmly upon the adjacent walls *b²* of the socket. The length of the step is, say, about four inches, or sufficient to form an easy rest or support for the lineman's foot in mounting the pole.

In the construction of poles adapted to carry conducting-wires it is usual, as before stated, to provide such poles with a series of fixed steps alternating with each other and arranged on opposite sides of the pole, as shown by Fig. 1, the lowest step *s* being, say, about six feet from the ground. In order to reach this step the linemen are forced to carry about with them a short ladder. By means of my invention, however, ladders are dispensed with, the linemen having to carry in their stead simply two or more of the step-pieces *a*—that is to say, the pole *p* is provided with the series of fixed steps *s*, as usual, but the lower portion of the pole intermediate of the lowest step and ground is provided with one or more plates *b*, which are arranged and permanently secured to the pole, so as to form, when combined with the removable pieces *a*, a continuation of the series of steps by which to mount the pole. Now, assuming that a lineman be required to ascend the pole *p*, he first takes from his pocket two steps *a* and affixes them to the two plates *b*, thereby forming steps by which he can readily reach the permanent steps *s*. Upon the completion of his duties he next, after descending to the ground, removes the two steps *a* from the plates and returns them to his pocket, the op-

eration just described being successively repeated on other poles adapted to the purpose, as desired. Obviously by employing a greater number of loose steps *a* the lineman may mount to a correspondingly-increased height if the pole be first provided with a similar number of permanent plates *b*. 35

I claim as my invention—

1. The improved step for electric-light poles, the same consisting of a base or plate *b*, adapted to be secured to the pole, provided on its front or outer face with upper and lower sockets, and a step or bracket *a*, having an end arranged to enter and interlock with each of said sockets, substantially as hereinbefore set forth. 40

2. The combination of a plate *b*, having formed in its face a lower socket *b*⁴ and an upper protected socket *b*³, and a removable step or bracket *a*, having an end arranged to enter each of said sockets and interlock therewith, substantially as described. 45

In testimony whereof I have affixed my signature in presence of two witnesses.

VAN A. THOMAS.

Witnesses.
